FREDERICK PERLEY PORTER, OF KELLOGG, IDAHO.

POWER ROCK-DRILL.

1,140,185.

Specification of Letters Patent.

Patented May 18, 1915.

Application filed March 1, 1913. Serial No. 751,441.

To all whom it may concern:

Be it known that I, FREDERICK P. PORTER, a citizen of the United States, and a resident of Kellogg, in the county of Shoshone and State of Idaho, have invented a new and Improved Power Rock-Drill, of which the following is a full, clear, and exact description.

The object of the invention is to provide a new and improved power rock drill of the hammer type and which is especially adapted for drilling holes in the sides and roof of a mine, and which is arranged to reduce vibrations to minimum, thus allowing easy handling of the machine without undue fatigue on the part of the operator and to withstand hard usage.

For the purpose mentioned use is made of a cylinder containing a hammer piston and provided with ports, a main admission and exhaust valve controlling the said cylinder ports and controlled by pressure from within the cylinder, a throttle valve connected with a source of pressure supply and connected with the said main admission and exhaust valve, a feed cylinder attached to the throttle valve, and a slide bar movable in the said feed cylinder and controlled by the motive agent passing through the throttle valve to the main admission and exhaust valve as well as to the feed cylinder.

A practical embodiment of the invention is represented in the accompanying drawings forming a part of this specification, in which similar characters of reference indicate corresponding parts in all the views.

Figure 1 is a side elevation of the power rock drill; Fig. 2 is a plan view of the same; Fig. 3 is an enlarged cross section of the same on the line 3—3 of Fig. 1; Fig. 3^a is a like view of the lower end of the feed cylinder and slide bar; Fig. 4 is an enlarged sectional side elevation of part of the power rock drill, the section being on the line 4—4 of Fig. 10; Fig. 5 is a cross section of the same on the line 5—5 of Fig. 10 and showing the hammer piston in lowermost position; Fig. 6 is a similar view of the same showing the main valve shifted, and the hammer piston in uppermost position, the section being on the line 6—6 of Fig. 10; Fig. 7 is a cross section of the same and similar to Fig. 5, but with the hammer piston in uppermost position; Fig. 8 is a similar view of the same on the line 8—8 of Fig. 10; Fig. 9 is a sectional plan view of

the throttle valve; and Fig. 10 is a sectional plan view of the main admission and exhaust valve and the muffler, the section being on the line 10—10 of Fig. 4.

In the main cylinder of the barrel A is mounted to reciprocate a piston B adapted to strike with its upper end against a tappet C mounted to slide in a reduced portion A' of the cylinder A, the said tappet C having a head C' adapted to be seated in the portion A² of the cylinder, and which is slightly enlarged relative to the portion A', so as to prevent the tappet C from dropping down too far. The head C' of the tappet C is adapted to strike against the terminal of the shank of the drill D mounted to slide in a chuck E held in the upper tapering bore A³ of the cylinder A and removably fastened in place therein by a cap E' and bolts E², as plainly indicated in Figs. 1, 2 and 3.

The lower end of the hammer piston B is provided with a reduced portion or a pin B' adapted to pass into a central port a formed in the cylinder head A⁴ closing the lower end of the main cylinder A. Against the cylinder head A⁴ abuts the main admission and exhaust valve F surrounded by a muffler shell G spaced from the exterior surface of the valve F to form an annular chamber G' into which passes the exhaust motive agent from the cylinder A to muffle the exhaust, as hereinafter more fully explained. Against the bottom cap F' of the main admission and exhaust valve F and against the lower end of the muffler shell G abuts the upper end of the casing H² of a throttle valve H connected with an inlet I to which a hose is secured for conducting the motive agent, such as compressed air, into the throttle valve H, from which the motive agent is directed into the main admission and exhaust valve F to pass into the ends of the cylinder A with a view to reciprocate the hammer piston B therein, as hereinafter more fully explained. On the inlet I is secured a horizontally-extending handle J adapted to be taken hold of by the operator for turning the power rock drill during the drilling operation to facilitate the boring of the hole by the drill D.

To the lower reduced end H' of the casing H² of the throttle valve H is secured the upper end of a feed cylinder K by the use of a yoke L, and in the said feed cylinder K is mounted to reciprocate a piston N to which is secured a slide bar O passing

through a cap K' attached to the lower end of the feed cylinder K, as plainly indicated in Figs. 1 and 3^a. The outer end of the slide bar O is preferably provided with a point 5 O' adapted to be set on the floor of the mine to yieldingly support the power drill during the drilling operation and to feed the drill D in the drill hole. The yoke L is fitted onto the casing H² of the throttle valve H 10 and is provided with an exterior flange L' connected by bolts L² with an integral flange A⁵ arranged on the lower end of the main cylinder A so as to securely fasten the feed cylinder K to the throttle valve casing H², 15 and to hold the throttle valve H, the main valve F and the muffler shell G in position on the cylinder A and in axial alinement therewith, as will be readily understood by reference to the drawings.

20 The casing F² of the main admission and exhaust valve F is provided with two concentric bores F² and F⁴, in which is mounted to slide a piston valve having a shank F⁵ and pistons F⁶, F⁷ and F⁸, of which the pistons F⁶ and F⁷ fit into the bore F³ while the larger piston F⁸ fits into the bore F⁴ which latter is closed by the cap F'. The lower end of the stem F⁵ extends into a bearing F⁹ formed in the cap F' so as to insure an 25 easy up and down sliding of the piston valve in the casing F². Into the upper smaller portion F² lead annular ports b, c, d and e, and into the larger lower bore F⁴ leads an annular port f. The upper port b is connected by diametrically arranged ports b' with vertical channels b² formed in the casing F² and in the cap F' to connect at their lower ends with a channel b³ formed in the top of the throttle valve casing H² under- 30neath the cap F' (see Fig. 4), and the said channel b³ is connected by a central port b⁴ with a port b⁵ leading to the recess H³ formed in the plug H⁴ of the throttle valve H, and which plug H⁴ is provided at its 35 outer end with a handle H⁵ under the control of the operator. The recess H³ opens at all times into the inlet I. When the piston valve is in lowermost position and the plug H⁴ is in the position shown in Fig. 4, 40 then the port b⁵ registers with the port b⁴ and consequently the motive agent can pass from the inlet I through the recess H³ and ports b⁵, b⁴ into the channel b³ and up through the channels b² and ports b' into 45 the annular port b and from the latter into the bore F³ to finally pass into the port a thus exerting a pressure against the reduced end B' of the hammer piston B to move the latter in an upward direction. It is understood 50 that when the hammer piston B moves upward the reduced portion B' finally leaves the port a thus allowing the motive agent to pass into the lower end of the cylinder A to drive the hammer piston B upward 55 with considerable force to strike a blow on

the tappet C, which latter exerts its force against the drill D. During the time the hammer piston B is on the upward stroke the upper end of the cylinder A is connected with the annular port c, and for this purpose the upper end of the cylinder A is provided with two oppositely arranged ports g leading to channels g' formed in side wall of the cylinder A and extending through the head A⁴ into the valve casing F² 60 to connect with the said annular port c. Now when the piston valve is in lowermost position, as shown in Figs. 4 and 5, then the port c is connected with the port d by the space between the pistons F⁶, F⁷ of the piston valve, and the port d connects by diametrical ports h with the annular chamber G' formed between the muffler shell G and the exterior face of the casing F² so that the exhaust is muffled. 65

70 The annular chamber G' connects with a number of vertical channels H⁶ formed in the throttle valve casing H² and the lower ends of the channels H⁶ connect with similar channels L³ formed in the yoke L, and the said channels L³ lead to an annular chamber L⁴ formed in the lower end of the yoke L. The said chamber L⁴ has a reduced lower end for the escape of the exhaust in a downward direction over the feed cylinder K (see Fig. 5). 75

When the hammer piston B nears the end of its upward stroke it uncovers successively ports i and i' (see Figs. 6, 7 and 8) leading to a channel i² formed in the side wall of the cylinder A and extending through the head A⁴, the valve casing F² and along the top of the cap plate F' to open into the bottom of the large bore F⁴ so that the motive agent in the lower end of the cylinder A can 80 pass by way of the ports i, i' and channel i² into the bore F⁴ to press against the larger piston F⁸ so as to force the piston valve upward to the position shown in Figs. 6, 7 and 8. When this takes place the port a is closed and the ports b and c are connected with each other to allow the motive agent to pass up through the channels g' and by way of the ports g into the upper end of the cylinder A to act on the hammer piston B 90 therein with a view to force the same downward on the return stroke. 95

When the piston valve is moved into uppermost position as above described and shown in Figs. 6, 7 and 8, then the ports e and f are connected with each other (see Fig. 8) and the port e is connected with channels e' formed in the valve casing F², the head A⁴ and the lower end of the wall of the cylinder A, the said channels leading to ports e² opening into the cylinder A a short distance above the head A⁴. The port f connects by diametrical ports with the annular chamber G' of the muffler so that the exhaust motive agent in the lower end of 100

the cylinder can pass out of the same by way of the ports e^2 , channels e' , port e , bore F^3 , port f , ports f' into the annular chamber G' to finally pass by way of the channels 5 H^6 and L^3 and the chamber L^4 to the outside.

It will be noticed that during the downward stroke of the hammer piston B the exhaust takes place in the lower end of the 10 cylinder A in the manner just described until the hammer piston B closes the ports e^2 , and when this takes place the remaining portion of the motive agent in the lower end of the cylinder forms a cushion for the 15 descending hammer piston B to cushion the latter, at the same time compressing the motive agent to such an extent as to force the piston valve downward back into the original position shown in Fig. 4. When 20 this takes place the motive agent is admitted to the lower end of the cylinder A to force the hammer piston B upward therein, and then the above operation is repeated.

The hammer piston B when moving into 25 a lowermost position uncovers a port j and when it moves into an uppermost position it uncovers a port j' . The ports j and j' lead to a vertical channel j^2 formed in the wall of the cylinder A and its head A^4 (see Fig. 30 4), and the lower end of the channel j^2 opens into the annular muffler chamber G' so that the upper end of the cylinder A is immediately relieved of pressure by way of the port j and channel j^2 at the time the 35 hammer piston B nears a lowermost position. In a like manner the lower end of the cylinder A is relieved of pressure by way of the port j' and channel j^2 at the time the hammer piston B moves into upper- 40 most position. The stem F^5 of the piston valve is provided with a channel k opening at its lower end into the bearing F^6 and terminating at its upper end in a diametrical port k' opening into the small bore F^3 intermediate the pistons F^6 and F^7 so that the bearing F^6 is relieved of all pressure and an 45 easy up and down sliding movement of the piston valve is had. The plug H^4 of the throttle valve H is provided with a port l directly opposite the port b^5 and leading 50 into the recess H^3 . The port l connects by a port n with the upper end of the feed cylinder K to admit the motive agent into the said cylinder at the time the plug H^4 is in 55 an open position. Into the port l opens a feed port o to permit of feeding compressed air into the upper end of the feed cylinder K at the time the plug H^4 is turned from the closed position into such a position that the 60 ports l and b^5 are still out of register with their ports n and b^4 to allow of forcing the feed cylinder K and the parts connected therewith upwardly until the point of the 65 drill D is in engagement with the rock, after which the plug H^4 is turned into full

open position to reciprocate the hammer piston B, as above described, and to feed the drill in the drill hole owing to the pressure in the feed cylinder K against the piston N. The throttle valve plug H^4 is provided 70 with an exhaust groove p leading to the outside and adapted to register with the port l at the time the said plug H^4 is in closed position so that the air pressure in the feed cylinder K can pass out of the same, thus 75 permitting the drill D to drop back.

The piston N is provided at the top with a spring coupling head N' adapted to engage a recess H^7 in the casing H^2 of the throttle valve to hold the said piston N and 80 the slide bar O in withdrawn position within the feed cylinder K at the time the power rock drill is moved about from place to place prior to being set up. It is understood that when pressure is admitted into the cylinder 85 K by way of the small feed port o , as above described in the drawings, the piston N is forced outward in the cylinder K and the coupling head N' is disengaged from the recess H^7 . 90

It is understood that the exhaust passing out of the ends of the cylinder A passes into the annular muffler chamber G' so that the motive agent is free to expand therein, and then the exhaust passes through the 95 channels H^6 and L^3 into another chamber L^4 in which the motive agent is again expanded to finally pass out of the chamber L^4 into the open air, thus thoroughly muffling the exhaust in its outward passage. By exhausting the air downward in the direction of the axis of the drill the exhaust air is not liable to spread the dust or cuttings. From the foregoing it will be seen that the hammer piston B is only cushioned on the 100 return or downward stroke and the force of the compressed air compressed by the reduced portion B' in the compressed air port a now moves the piston valve F downward into starting position to again admit 105 the motive agent to the lower end of the cylinder A to drive the hammer piston B outward. 110

The reduced end B' of the hammer piston B in entering the port produces sufficient 115 compression to at least equal that of the live motive agent, the object being to steady the drill when in operation, as in this class of drills suspended or held up by a column of air in the feed cylinder the rebound 120 caused by the sudden intake and exhaust of the motive force coupled with the rapid reciprocating of the hammer (800 to 1,000 blows per minute) causes a vibration very tiresome to the operator. This arrangement in my drill seems to have the desired effect as it is unusually steady. By the use of the auxiliary exhaust ports the back pressure on the hammer is reduced by allowing 125 a small amount of exhaust to escape while 130

at a comparatively high pressure thus relieving the hammer of some of its obstruction at a time when the obstruction is at its highest point thereby insuring a more rapid 5 piston travel and harder blow on the tappet.

Having thus described my invention I claim as new and desire to secure by Letters Patent:

16. 1. A power rock drill, comprising a main cylinder having in its wall a longitudinal channel communicating therewith, a hammer piston in the cylinder, an admission and exhaust valve on one end of the cylinder, 15 and consisting of a valve casing provided with a central bore in two diameters, a plurality of longitudinal ports leading to the smaller bore and a port leading from the channel of the cylinder to the larger bore, 20 and a piston valve in said bore and having spaced pistons fitting in the said bore, a throttle valve casing held on the piston valve casing and having a channel in its top leading to the longitudinal ports of the 25 valve casing and a longitudinal port leading to the channel, and a throttle valve in the said casing, said valve controlling said port and connected with a fluid supply.
2. A power rock drill, comprising a main 30 cylinder, a hammer piston on the cylinder, a piston valve casting on one end of the cylinder, a piston valve in the casting, a muffler chamber surrounding the piston valve casting and communicating with the bore thereof, 35 a throttle valve casting on the piston valve casting, and having ports communicating with the muffler chamber and leading to the atmosphere, and a throttle valve in the casting and connected with a fluid supply.
40. 3. A power rock drill, comprising a main cylinder a hammer piston mounted to reciprocate in the said cylinder, and an admission and exhaust valve held on one end of the said main cylinder, said valve comprising a body having a central bore, in 45 two diameters, ports leading to the bore, and a chamber in the bottom thereof, and a piston valve in the bore of the body and having three pistons of which one is larger 50 than the other two, said piston valve having its lower end reduced and extending into the chamber of the body and provided with a transverse opening and a central longitudinal channel leading from said opening 55 out through its lower end.
4. A power rock drill, comprising a main cylinder provided at its outer and inner ends with admission ports for the motive agent to alternately pass into the ends of the cylinder, the said outer end port also serving as 60 an exhaust port for the outer end of the cylinder, the latter also having an inner exhaust port leading from the cylinder intermediate the ends thereof, and the said cylinder also having a valve port leading from the cyl- 65
- inder at a point above the said inner exhaust port, a hammer piston reciprocating in the said cylinder, a main valve having a valve casing provided with ports and attached to the inner end of the cylinder, and a piston valve reciprocating in the said valve casing, the said piston valve having three pistons fittings in said bore and controlling the said casing ports, the latter connecting with the said cylinder ports, a throttle valve 70 connected with a motive agent supply and connected with the said main valve, and a muffler shell surrounding the said valve casing and forming a muffler chamber therewith, the exhaust ports opening into the said muffler chamber and the latter opening into the atmosphere. 75
5. A power rock drill, comprising a cylinder having inlet and exhaust ports, a hammer piston in the cylinder, an admission and exhaust valve governing the inlet and exhaust of the cylinder, an annular muffler chamber surrounding the valve and a throttle valve casing and having ports communicating with the muffler chamber and extending through the said casing to the atmosphere. 80
6. A power rock drill, comprising a cylinder having inlet and exhaust ports, a hammer piston in the cylinder, an admission and exhaust valve controlling the inlet and exhaust ports of the cylinder, a throttle valve casing having ports extending therethrough and opening to the atmosphere, a shell between the cylinder and the throttle valve 85 casing, said shell surrounding the admission and exhaust valve and spaced therefrom to form a muffler chamber communicating with the ports of the throttle valve casing, and means for securing the throttle valve casing to the cylinder. 90
7. A power rock drill, comprising a cylinder having longitudinal passages, ports leading from said passages into the cylinder and a port in its lower end wall, a hammer piston in the cylinder and having a reduced portion adapted to enter the port in the end of the cylinder, a piston valve casing at the end of the cylinder and having a bore in two diameters and ports leading to the bore, a piston valve in the bore and having three pistons fitting said bore, a throttle valve casting below the piston valve casing and having a port leading to the ports of the said piston casing, a throttle valve in the casing and connected with a fluid supply and means for securing the said valve casing to the cylinder. 100
8. In a power rock drill, a cylinder having a port in one head, a hammer piston in the cylinder, and having a reduced end adapted to enter the said port, and an admission and exhaust valve on the end of the cylinder having the port therein, said valve consisting of a valve casing having a cen- 105
- 110

- 125
- 130

tral bore of two diameters and a plurality of ports leading to the bore and a piston valve in the said bore and having three spaced pistons of which one is larger than 5 the other two, said piston valve being adapted to close the port of the cylinder.

9. In a power rock drill, a cylinder having a port in one head, a hammer piston in the cylinder, and an admission and exhaust 10 valve at the end of the cylinder having the port therein, said valve consisting of a valve casing having a central bore of two diameters and a chamber at one end, and a piston valve in the said bore and having three 15 spaced pistons of which one is larger than

the other two, the stem of the piston valve projecting below the lowermost piston into the said chamber and having a longitudinal passage leading out through its lower end and a transverse opening at the upper end of 20 the longitudinal passage, above the uppermost piston.

In testimony whereof I have signed my name to this specification in the presence of two subscribing witnesses.

FREDERICK PERLEY PORTER.
